W. COOPER.

BOTTLE CAPPING MACHINE.

APPLICATION FILED MAR. 2, 1903. RENEWED JUNE 23, 1904.

899,861.

Patented Sept. 29, 1908.

UNITED STATES PATENT OFFICE.

WILLIAM COOPER, OF CINCINNATI, OHIO, ASSIGNOR, BY MESNE ASSIGNMENTS, TO THE BOTTLE CAPPING MACHINE COMPANY, OF NEW YORK, N. Y., A CORPORATION OF NEW YORK.

BOTTLE-CAPPING MACHINE.

No. 899,861.

Specification of Letters Patent. Patented Sept. 29, 1908.

Application filed March 2, 1903, Serial No. 145,664. Renewed June 23, 1904. Serial No. 213,819.

To all whom it may concern:

Be it known that I, WILLIAM COOPER, a citizen of the United States, and resident of Cincinnati, county of Hamilton, State of Ohio, have invented certain new and useful improvements in Bottle-Capping Machines, of which the following is a specification.

This invention relates to certain improvements in capping machines and has more particularly in view to improve that class of capping machines in which a capsule of pliable material is applied to the article to be capped.

One of the objects of the invention is to provide a machine in which the cap applying device or devices are out of contact with the article to be capped when the same is positioned in the machine, the cap applying device being thereafter brought into operative relation with the capsule by a smooth and uniform movement and without shock or jar.

A further object of the invention is to provide a capping machine in which the cap applier is caused to operate by centrifugal force, the movement of said device being controlled in such a way as to prevent any substantial shock or jar upon the article to be capped.

35 A further object of the invention is to produce a capping machine in which the cap applier is thrown into and out of operative relation with the article to be capped by means controlled by said article.

35 A further object of the invention is to produce a capping machine embodying a rotating head and a cap applier carried thereby, the cap applier being caused to move into operative relation with the article to be capped by the centrifugal force developed by the rotation of the head, the machine being so constructed as to enable the speed of rotation of the head to be varied according to whether there be an article in the machine to be capped.

With these and other objects in view the invention consists in certain constructions and in certain parts, improvements and combinations that will be hereinafter described and then more fully pointed out in the claims hereunto appended.

In the accompanying drawings, in which like characters of reference indicate the same parts: Figure 1 is a longitudinal sectional plan view of a capping machine em-

bodying the invention. Fig. 2 is a front elevation of the cap applying devices of the machine and connected parts. Fig. 3 is a detail view of one of the cap applying devices. Fig. 4 is a detail view of one of the arms for carrying the cap applying devices. Fig. 5 is a detail view of the means for causing a uniform movement of the cap applying devices.

In the particular embodiment of the invention illustrated in the drawings there is provided a carrier upon which the cap applier, to be hereinafter described, is mounted. The carrier illustrated comprises a head A which is mounted upon a shaft a. In the particular construction illustrated the shaft and head are horizontally arranged and are supported by a bearing b suitably mounted in the machine.

The head is arranged to be rotated and may be rotated by any desired mechanism. In the particular construction shown an electric motor B is utilized for this purpose, this motor being of any approved design. In order to enable the motor to effect the rotation of the head the head is provided with a gear wheel a', which meshes with a gear wheel b' mounted upon a shaft b' of the motor.

The cap applier which is carried by the head may be variously constructed, but in its preferred form it will be so constructed as to be caused to be brought into operative relation with the article to be capped by the centrifugal force developed by the rotation of the head.

In the particular embodiment of the invention shown the cap applier will comprise a plurality of arms carrying applying devices, such as spinning devices. These arms are mounted upon the head so that these cap applying devices carried by them will, as has been before indicated, move into operative relation with the article to be capped by reason of the centrifugal force developed in the rotation of the head. In the construction shown this is effected by pivoting the arms to the head, the arms being provided with weights which overbalance the spinning devices and which are caused to move outward in the rapid rotation of the head, thus carrying the spinning devices inward. In the preferred construction and as shown these arms consist of three arm levers c' pivoted to posts c upon the head, one of the

arms of each of these levers carrying a weight C^3 , another arm carrying a post C^2 , upon which the spinning device C is rotatably mounted, and the third arm C^4 carrying a pin C^5 , the purpose of which will be hereinafter explained.

In the preferred construction a regulating device is provided which opposes the tendency of the weights to move away from and 10 the cap applicer to move toward the article to be capped under the action of the centrifugal force developed by the head, this regulating device thus preventing any sudden movement of the weights and spinning devices and also operating to disengage the 15 spinning devices from the article to be capped when the rotation of the head decreases sufficiently to allow the regulating device to overcome the centrifugal force developed. In the preferred construction this 20 regulating device will consist of a resilient band D which connects the arms on which the spinning devices and weights are mounted. Preferably this band D will consist of 25 a rubber band embracing the weighted ends of the levers. The band when so arranged is readily removable from the apparatus and bands of varying strength can readily be substituted according to the character of the 30 cap which the machine is to be used to apply.

It is of importance in a machine of this character that the cap applying devices move uniformly into and out of operative relation with respect to the article to be capped so 5 that the devices may act upon and cease to act upon the cap or capsule simultaneously. In the preferred construction, therefore, means will be provided which cause a uniform movement of these devices. While 10 these means may vary in construction they will preferably consist of a connecting device of such a character as to cause all the arms to move when any one of the arms moves. In the construction shown there is 15 provided a ring or disk E provided with slots or notches e , which ring is rotatably mounted upon the head. The projecting arms C^4 before referred to of the levers carry pins C^5 which project into the slots e 20 of the ring. This ring E , as has been pointed out, is rotatably mounted on the head and it follows, therefore, that when any one of the weighted lever arms moves the ring will be moved by it and the lever arms thus 25 simultaneously moved.

While any suitable motor may be employed for driving the head, the construction will be preferably such that the speed of the motor may be controlled by the article 30 to be capped; that is to say, that the speed of the motor will be increased when the article to be capped is inserted into the machine and decreased when the article is withdrawn from the machine. An electric motor readily lends itself to the requirements indicated

and for this reason in the preferred construction, as has been illustrated an electric motor will be employed.

The devices by which the speed of the electric motor is increased and diminished may 70 be widely varied. Preferably, however, a resistance will be employed, the circuits being so arranged that the current may be sent directly through the motor and around the resistance when the motor and head are to 75 run at full speed, with the cap applying devices in operative relation with the article to be capped, the current being sent through the resistance to the motor when it is desired to diminish the speed of the motor and head. 80

The resistance may be of any suitable character, as, for instance, a lamp M , and, as shown, a conductor H leads to a binding post on the resistance and then to a contact spring G carried on the ring a^2 of insulating material carried on the shaft a . The ring of insulating material a^2 carries another contact spring G' and from this contact spring a conductor H' leads to a binding post on the resistance and then to a binding post on the motor, the return conductor leading from the other binding post on the motor as is usual. It is apparent that when the circuit between the contacts G, G' is closed the current will be sent around the resistance directly into the motor. When, however, the circuit between the contacts G, G' is broken, the current will flow through the resistance into the motor, thus diminishing the speed of the motor. 95

The devices by which the circuit between the contacts G and G' is made and broken may widely vary in character. In the construction shown, there is provided a sliding rod F which is located within the shaft a 105 said rod carrying at one end a button or support f against which the article to be capped is pressed. The other end of the sliding rod F carries a conducting ring f' mounted upon a non-conducting support f^2 . The rod F is 110 normally held by a spring f^3 in such position that the circuit closer f' is out of contact with the contacts G and G' . When, however, the rod is pushed inward as it is 115 when the article to be capped is pressed against it, the circuit closing ring f' is brought against the contacts G, G' , and the current will be sent around the resistance directly into the motor. When the parts are in the position shown in Fig. 1, the current 120 is flowing through the resistance into the motor. When, however, a bottle or other article to be capped is inserted, the circuit around the resistance is closed and the current is sent directly into the motor, thereby 125 causing the motor to rotate the head rapidly. The centrifugal force developed by the rapid rotation of the head causes the weights of the arms carrying the cap applying devices to move outward against the tension of the 130

yielding regulating ring D and the cap applying devices to move inward, the movement taking place without any substantial shock or jar and being rendered absolutely uniform by the ring E. When the cap has been spun down into place upon the bottle or other article and the same is withdrawn, the spring f moves the sliding rod F forward, breaks the contact between the fingers G, G', thus shunting the current through the resistance, and diminishing the rotation of the motor and the amount of centrifugal force developed by the head. The ring D now contracts, immediately throwing the spinning devices out of contact with the article to be capped, this movement being also rendered uniform by the ring E.

It will be observed that the arms carrying the cap applying devices and the weights are so mounted as to move across the face of the head and in planes substantially parallel thereto. This arrangement of the arms makes an exceedingly compact and effective construction, one which can be readily constructed and one in which the parts are readily accessible. Furthermore, this construction readily lends itself to the removal and replacing of the yielding regulating ring D whenever it is desired to change this ring to vary the force exerted thereby.

While the specific embodiment of the invention illustrated in the drawing has been demonstrated by practical use to be an exceedingly efficient one, the invention may be embodied in constructions which differ widely therefrom. The invention is not, therefore, to be limited to the specific details of construction hereinbefore described and illustrated in the accompanying drawing.

40. What is claimed is:

1. In a capping machine, the combination with a rotating carrier, of a cap applicator mounted thereon and caused to move into operative relation with the article to be capped by the centrifugal force developed by the rotation of the carrier, and a regulating means operating to oppose the movement of the cap applicator with respect to the article to be capped, substantially as described.

2. In a capping machine, the combination with a rotating carrier, of a cap applicator mounted thereon, said cap applicator comprising a plurality of applying devices and being caused to move into operative relation with the article to be capped by the centrifugal force developed by the rotation of the carrier, and a regulating means operating to oppose the movement of the cap applicator with respect to the article to be capped, substantially as described.

3. In a capping machine, the combination with a rotating carrier, of a cap applicator mounted thereon and caused to move into operative relation with the article to be

capped by the centrifugal force developed by the rotation of the carrier, and a yielding regulating means operating to oppose the movement of the cap applicator with respect to the article to be capped, substantially as described.

4. In a capping machine, the combination with a rotating carrier, of a cap applicator mounted thereon, said cap applicator comprising a plurality of applying devices and being caused to move into operative relation with the article to be capped by the centrifugal force developed by the rotation of the carrier, and a yielding regulating means operating to oppose the movement of the cap applicator with respect to the article to be capped, substantially as described.

5. In a capping machine, the combination with a rotating carrier, of a plurality of levers pivoted thereon, cap applying devices carried by the levers, weights carried by the levers whereby the centrifugal force developed by the rotation of the carrier causes the weights to move away from and the applying devices toward the article to be capped, and a regulating means operating to oppose the movement of the applying devices with respect to the article to be capped, substantially as described.

6. In a capping machine, the combination with a rotating carrier, of a weighted cap applicator mounted thereon, and caused to move into operative relation with the article to be capped by the centrifugal force developed by the rotation of the carrier, said applicator moving across the face of the carrier and in planes substantially parallel thereto, substantially as described.

7. In a capping machine, the combination with a rotating carrier, of a cap applicator mounted thereon, said applicator comprising a plurality of weighted levers carrying cap applying devices, said applying devices being caused to move into operative relation with the article to be capped by the centrifugal force developed by the rotation of the carrier, said cap applicator moving across the face of the carrier and in planes substantially parallel thereto, substantially as described.

8. In a capping machine, the combination with a rotating carrier, of a cap applicator comprising a plurality of weighted arms pivoted to the carrier and moving into operative relation with the article to be capped by the centrifugal force developed by the rotation of the carrier, said arms moving across the face of the carrier in planes substantially parallel with said face, and a yielding regulating means operating to oppose the movement of the cap applicator with respect to the article to be capped, substantially as described.

9. In a capping machine, the combination with a rotating carrier, of a cap applicator comprising a plurality of weighted arms

- mounted on the carrier and carrying cap applying devices, said applying devices being caused to move toward the article to be capped by the centrifugal force developed by the rotation of the carrier; and a resilient regulating band operating to oppose the movement of the applying devices toward the article to be capped, substantially as described.

10. In a capping machine, the combination with a rotating carrier, of a cap applier comprising a plurality of weighted arms pivoted to the carrier and carrying cap applying devices, said applying devices being caused to move toward the article to be capped by the centrifugal force developed in the rotation of the carrier, and a resilient regulating band surrounding the weighted ends of the arms, substantially as described.

15. In a capping machine, the combination with a rotating head, of a cap applier comprising a plurality of weighted arms carrying cap applying devices and mounted upon the head, said cap applying devices being caused to move into operative relation with the article to be capped by the centrifugal force developed by the rotation of the carrier, and means whereby the movement of the cap applying devices toward the article to be capped is made uniform, substantially as described.

20. In a capping machine, the combination with a rotating head, of a cap applier comprising a plurality of weighted arms pivoted on the head and carrying cap applying devices, said cap applying devices being caused to move into operative relation with the article to be capped by the centrifugal force developed by the rotation of the head, and means whereby the movement of the cap applying devices toward the article to be capped is made uniform, substantially as described.

25. In a capping machine, the combination with a rotating head, of a cap applier comprising a plurality of weighted arms pivoted on the head and carrying cap applying devices, said cap applying devices being caused to move into operative relation with the article to be capped by the centrifugal force developed by the rotation of the head, and means whereby the movement of the cap applying devices toward the article to be capped is made uniform, substantially as described.

30. In a capping machine, the combination with a rotating head, of a cap applier comprising a plurality of weighted arms pivoted on the head and carrying cap applying devices, said cap applying devices being caused to move into operative relation with the article to be capped by the centrifugal force developed by the rotation of the head, and means whereby the movement of the cap applying devices toward the article to be capped is made uniform, substantially as described.

35. In a capping machine, the combination with a rotating head, of a cap applier comprising a plurality of weighted arms pivoted on the head and carrying cap applying devices, said cap applying devices being caused to move into operative relation with the article to be capped by the centrifugal force developed by the rotation of the head, and means whereby the movement of the cap applying devices toward the article to be capped is made uniform, substantially as described.

40. In a capping machine, the combination with a rotating head, of a cap applier comprising a plurality of weighted arms pivoted on the head and carrying cap applying devices, said cap applying devices being caused to move into operative relation with the article to be capped by the centrifugal force developed by the rotation of the head, and means whereby the movement of the cap applying devices toward the article to be capped is made uniform, substantially as described.

45. In a capping machine, the combination with a rotating head, of a cap applier comprising a plurality of weighted arms pivoted on the head and carrying cap applying devices, said cap applying devices being caused to move into operative relation with the article to be capped by the centrifugal force developed by the rotation of the head, and a rotatable connecting device for causing a uniform movement of the applying devices, substantially as described.

50. In a capping machine, the combination with a rotating head, of a cap applier comprising a plurality of weighted arms pivoted on the head and carrying cap applying devices, said cap applying devices being caused to move into operative relation with the article to be capped by the centrifugal force developed by the rotation of the head, and a rotatable connecting device for causing a uniform movement of the applying devices, substantially as described.

55. In a capping machine, the combination with a rotating head, of a cap applier comprising a plurality of weighted arms mounted on the head and carrying cap applying devices, said cap applying devices being caused to move into operative relation with the article to be capped by the centrifugal force developed by the rotation of the head, a ring movably mounted on said head, and connections between said ring or disk and the arms whereby the movement of the

applying devices is caused to be uniform, substantially as described.

15. In a capping machine, the combination with a rotating head, of a cap applier comprising a plurality of weighted arms pivoted on the head and carrying cap applying devices, said cap applying devices being caused to move into operative relation with the article to be capped by the centrifugal force developed by the rotation of the head, and a notched disk for causing a uniform movement of the applying devices, substantially as described.

16. In a capping machine, the combination with a rotating head, of a cap applier comprising a plurality of weighted arms pivoted upon the head and carrying spinning devices, the spinning devices being caused to move toward the article to be capped by the centrifugal force developed by the rotation of the head, a yielding regulating means opposing the movement of the spinning devices, and means for causing the movement of the spinning devices with respect to the article to be capped to be uniform, substantially as described.

17. A capping machine consisting of a rotating head, a cap applier comprising a plurality of weighted arms pivoted on the head, said arms carrying spinning devices, the spinning devices being moved into operative relation with the article to be capped by the centrifugal force developed by the rotation of the head, a resilient band surrounding the weighted ends of the arms; and a rotating connecting device for causing a uniform movement of the spinning devices, substantially as described.

18. A capping machine comprising a rotating head, a cap applier comprising a plurality of weighted arms pivoted on the head, said arms carrying spinning devices, the spinning devices being moved into operative relation with the article to be capped by the centrifugal force developed by the rotation of the head, the resilient band surrounding the weighted ends of the arms, and a notched disk for causing a uniform movement of the spinning devices, substantially as described.

19. In a capping machine, the combination with a rotating head, of a cap applier comprising a plurality of three-armed levers pivoted upon the head, weights on one of the arms of each of said levers and spinning devices on another of the arms of said levers, a notched disk connecting the third of the arms of the levers, and a resilient band connecting the weighted arms of the levers whereby the spinning devices are caused to move uniformly towards and away from the article to be capped by the rotation of the head, substantially as described.

20. In a capping machine, the combination with an electric motor, of a rotating capping

device driven by the motor, a resistance through which the current normally flows into the motor, a suitable circuit leading from the source of electrical supply through 5 the resistance to the motor, and around the resistance directly to the motor, and means for causing the current to be sent either through the resistance or directly into the motor, whereby the speed of the motor is 10 varied, substantially as described.

21. In a capping machine, the combination with an electric motor, of a rotating capping device driven by the motor, a resistance through which the current normally 15 flows into the motor, a suitable circuit leading from the source of electrical supply through the resistance to the motor and around the resistance directly to the motor, and means operated by the article to be 20 capped for causing the current to be sent either through the resistance or directly into the motor, whereby the speed of the motor is varied, substantially as described.

22. In a capping machine, the combination with an electric motor, of a rotating capping device driven by the motor, a resistance through which the current normally flows into the motor, a suitable circuit leading 25 from the source of electrical supply through the resistance to the motor and around the resistance directly to the motor, and a sliding rod moved by the article to be 30 capped for causing the current to be sent either through the resistance or directly into 35 the motor, whereby the speed of the motor is varied, substantially as described.

23. In a capping machine, the combination with a head, of a cap applicer comprising a plurality of weighted arms carrying 40 cap applying devices and mounted on the head, an electric motor for operating the head, a resistance, a suitable circuit leading from the source of electrical supply through the resistance to the motor and around the 45 resistance directly to the motor, and means operated by the article to be capped for causing the current to be sent either through the resistance or directly into the motor, whereby the speed of the motor is varied, 50 substantially as described.

24. In a capping machine, the combination with a rotating head, a cap applicer comprising a plurality of weighted arms

carrying spinning devices pivoted upon the head, said applying devices being caused to 55 move into operative relation with the article to be capped by the centrifugal force developed by the rotation of the head, a yielding regulating device for opposing the movement of the spinning devices with respect 60 to the article to be capped, a connecting means for causing the movement of the spinning devices to be uniform, an electric motor for rotating the head, a resistance, a circuit leading from the source of electrical 65 supply through the resistance to the motor, and around the resistance to the motor, and means under the control of the article to be capped for causing the current to be sent either through the resistance or directly into 70 the motor whereby the speed of rotation of the head is varied, substantially as described.

25. In a capping machine the combination with a head, of a cap applicer mounted 75 thereon and caused to move into operative relation with the article to be capped by the centrifugal force developed by the rotation of the head, rotating means, and means thrown into operation by the article to be 80 capped for causing the rotating means to rotate the head at a speed sufficient to cause the cap applicer to move by the centrifugal force developed into operative relation with the article to be 85 capped.

26. In a capping machine, the combination with a rotating head, of a cap applicer mounted thereon and caused to move into operative relation with the article to be 90 capped by the centrifugal force developed by the rotation of the head, and means for varying the speed of rotation of the head, substantially as described.

27. In a capping machine, the combination with a rotating head, of a cap applicer 95 mounted thereon and caused to move into operative relation with the article to be capped by the centrifugal force developed by the rotation of the head, and means thrown into operation by the article to be 100 capped for varying the speed of rotation of the head, substantially as described.
